CLAIM

We claim the ornamental design for a part for hook assembly, as shown and described.

DESCRIPTION

FIG. 1 is a front right perspective view of an embodiment of a part for hook assembly showing our new design;
FIG. 2 is a rear right perspective view thereof;
FIG. 3 is a rear perspective view thereof;
FIG. 4 is a front view thereof;
FIG. 5 is a rear view thereof;
FIG. 6 is a left view thereof;
FIG. 7 is a right view thereof;
FIG. 8 is a top view thereof; and,
FIG. 9 a bottom view thereof.
